POWER TRANSMISSION

Raymond C. Griffith, Detroit, Mich., assignor to
 Vickers Incorporated, Detroit, Mich., a corpora-
 tion of Michigan

Application November 18, 1938, Serial No. 241,121

2 Claims. (CL 121—157)

This invention relates to power transmissions, particularly to those of the type comprising two or more fluid pressure energy translating devices one of which may function as a pump and another as a fluid motor.

The invention is particularly concerned with a transmission system adapted for operation of a reversible double-acting motor, for example, the operating ram of a hydraulic press, shear, punch, or the like. For certain classes of work such as metal drawing, punching, and shearing, mechanical crank-operated presses have been widely used in the past due to their greater operating speeds, and it is only within the past few years that hydraulic press speeds have approached the point where they can successfully compete with mechanical presses in this class of work.

The usual mechanical press is controlled by a one-revolution clutch. This clutch is controlled from a lever or foot pedal in such a way that when the pedal is operated, the press is started and goes through one cycle, consisting of a forward and a return stroke, coming to rest at the end of the return stroke if the pedal has in the meantime been released. If, however, the pedal is held in the starting position, the press will operate in continuously repeated cycles so long as the pedal is held there, and when the pedal is released the press will stop at the end of the next return stroke. Control systems for hydraulic presses are commonly arranged so that it is necessary to manually initiate each separate cycle or if continuously repeated cycles are desired, it is necessary to operate a starting control to start the press in operation and to later operate a stopping control when it is desired to terminate the operation.

It is an object of the present invention to provide an improved hydraulic transmission system of the class described wherein simple control means is provided for permitting either single cycle or repeated cycle operations from a single control element which, when moved to one position, will start the system in operation either through one cycle or through repeated cycles, depending upon how long the control element is maintained in the starting position.

It is a further object to provide a system of this character with improved emergency stopping mechanism which is effective to stop the motor whether it is on an advancing stroke or on a return stroke and which emergency control may be effected by operation of a single lever in one direction regardless of whether the motor is on its advancing or returning stroke.

Further objects and advantages of the present invention will be apparent from the following description, reference being had to the accompanying drawing wherein a preferred form of the present invention is clearly shown.

In the drawing the single figure is a diagrammatic view of a power transmission system incorporating a preferred form of the present invention.

The pump 18 is adapted to be driven by a prime mover such as an electric motor 12 to withdraw fluid from a tank 14 through a suction conduit 16 and deliver the same to a delivery conduit 18 having a conventional relief valve 20 for by-passing fluid to the tank through a conduit 22 whenever a predetermined safe pressure is exceeded in the conduit 18.

The conduit 18 leads to the pressure port 24 of a pilot-operated four-way valve 26. The tank ports 28 of the valve 26 are connected by a conduit 30 to the tank. Cylinder ports 32 and 34 connect by conduits 36 and 38 to the head and rod ends respectively of a cylinder 40. Within the cylinder 40 is reciprocably mounted a piston 42 having a rod 44 to which is attached a platen 46 of a hydraulic press. The cylinder 40 and piston 42 constitute a reversible double-acting fluid motor, although it will be understood that other types of fluid motor including those of the rotary type may be equally suitable for use with the present invention, for example, under conditions where alternately reversing rotary movement may be required.

Interposed in the conduit 38 is a pressure responsive foot valve 48 of well-known construction comprising a spool 50 normally held to the left in closed position by a spring 52 and adapted to be moved to the right by pressure in the conduit 38 transmitted through a conduit 54 to the left-hand end of the spool 50. The valve 48 is preferably adjusted so that the pressure required to open the same and which is produced in the rod end of cylinder 40 by the gravity load on the piston 42 is sufficient to provide a source of fluid for pilot control purposes. A check valve 56 permits free flow through the conduit 38 into the rod end of the cylinder 40.

The pilot-operated four-way valve 26 is provided with a spool 58 having a land 60 which blocks the port 34 in center position and a land 62 which is beveled off on its opposite sides to permit free flow from port 24 to port 28 when the valve is in center position. The spool 58 has piston stems 64 and 66 slidably mounted in bores 68 and 70 formed in the end caps 72 and 74. Con-

trol connections 76 and 78 communicate with the bores 68 and 70 by means of adjustable restrictions 80 and 82 in parallel with which are a pair of check valves 84 and 86. Emergency control connections 88 and 90 communicate with the bores 68 and 70 directly, that is, without passing through the restrictions and check valves.

The spool 58 is provided with a shoulder 92 at its right-hand end which is adapted to engage a detent 94 pivoted at 96 in the valve body and spring-biased in a counterclockwise direction to the position shown in the drawing. A suitable control lever 98 is provided for swinging the detent clockwise to release the same from engagement with the shoulder 92.

For the purpose of normally controlling the pilot-operated valve 26, a four-way pilot valve 100 is provided having ports P, T, 1 and 2. The latter are controlled by a rotor 102 which is shiftable forty-five degrees clockwise from the position shown to transpose the connections through the valve. Port P is connected by a conduit 104 with the conduit 38 at a point between the cylinder 40 and the foot valve 48. Port T is connected to tank by a conduit 106. Ports 1 and 2 connect by conduits 108 and 110 with the control connections 76 and 78 respectively.

The rotor of pilot valve 100 is provided with a lever 112 which may be controlled by suitable dogs 114 and 116 carried by an extension rod 118 secured to the platen 46. When the platen is in its uppermost position, the dog 114 shifts the lever 112 and rotor 102 into the position shown in the drawing. When the platen reaches its lowermost position the dog 116 contacts the lever 112 to shift the rotor 102 clockwise forty-five degrees and transpose the connections. The dog 116 may be adjustably mounted on the rod 118 and is adapted to be completely removed therefrom when it is desired to control the end point of the working stroke from the working pressure rather than from the position of the platen 46.

For this purpose the rotor 102 is provided with a second lever 120 adapted to be operated by a piston 122 slidably mounted in a cylinder 124 and urged to the left by a spring 126. The left end of cylinder 124 connects by a conduit 128 with the conduit 36, a suitable shut-off valve 130 being provided in the conduit 128. When, at the completion of a working stroke, the pressure builds up to a sufficient value to overcome the force of the spring 126, the piston 122 moves to the right shifting the lever 120 and rotor 102 in a clockwise direction to transpose the connections through pilot valve 100 in the same manner as when the same is shifted by the dog 116. The dog 116 and the piston 122 thus constitute alternative means for shifting the pilot valve 100 at the completion of a working stroke.

For purposes of emergency control a second rotary pilot valve 132 is provided which is similar to the pilot valve 100. The rotor 134 of valve 132 may be controlled by a hand lever 136 which is biased by a spring 138 in a clockwise direction and maintained in its center position as shown by a stop pin 140.

Port P of pilot valve 132 connects by a conduit 142 to the conduit 38 while port T connects by a conduit 144 to the emergency control connection 88. Port 2 connects by a conduit 146 to the conduit 36 while port 1 connects by a conduit 148 to the emergency control connection 90.

In operation, assuming the parts to be in the position shown in the drawing and that the mo-

tor 12 and pump 10 are operating, fluid is withdrawn from the tank 14 through the conduit 16 and delivered through conduit 18 to port 24 of valve 26 from which it passes out port 28 and through conduit 30 to tank. The pump 10 is thus bypassed with negligible resistance.

The piston 42 is held stationary because the oil in the rod end of the cylinder 40 is trapped from escaping through the conduit 38 both by the foot valve 48 and by the land 60 in the four-way valve 26. The platen 46 thus remains stationary.

To start a cycle of operations, the lever 98 is moved clockwise to retract the detent 94. Since pressure is maintained in the cylinder 70 through the conduit 104, ports P and 2 of valve 100, and conduit 110, the spool 58 shifts to the right at a speed determined by the setting of the restrictor 80 which determines the rate at which oil can be discharged from the cylinder 68 at the right-hand end of valve 26. Fluid, of course, enters the cylinder 70 freely through the check valve 86.

With the spool 58 thus shifted to its right-hand position port 24 is placed in communication with port 32 and port 28 is placed in communication with port 34. Oil thus passes from conduit 18 through conduit 36 to the head end of cylinder 40 causing the piston 42 to move downwardly discharging oil from the rod end through conduit 38, foot valve 48, ports 34 and 28, and conduit 30 to tank.

Assuming that the valve 130 is closed and the dog 116 is in place, as the platen approaches its lowermost position dog 116 will contact lever 112 shifting the rotor 102 clockwise and transposing the connections in pilot valve 100. Pressure oil from conduit 38 then passes through conduit 104, ports P and 1 of valve 100 and conduit 108 to the cylinder 68, thus shifting the spool 58 to the left at a speed determined by the setting of restrictor 82.

Oil discharged from the cylinder 70 passes through conduit 110, ports 2 and T of valve 100 and conduit 106 to the tank. With the spool 58 thus shifted to its leftmost position port 24 is placed in communication with port 34 and oil flows from conduit 18 through conduit 38 and check valve 56 to the rod end of cylinder 40. The piston 42 accordingly moves upwardly discharging oil from the head end of cylinder 40 through conduit 36, ports 32 and 28, and conduit 30 to tank. The same action takes place when the piston 122 is connected to cause shifting of valve 100 when a predetermined pressure builds up in line 36.

As the platen approaches its upper position, dog 114 contacts lever 112 to shift the rotor 102 counterclockwise into the position shown in the drawing. Pressure from conduit 38 is thus again transmitted through conduit 110 to the cylinder 70, shifting spool 58 to the left.

If, in the meantime, the lever 98 has been released to position the detent 94 in the path of the shoulder 92, the spool 58 will only shift as far as its center position, thus bringing the piston 42 to a stop and restoring the system to its starting condition previously described. If, however, the lever 98 has not been released prior to the shifting of valve 100, the spool 58 will shift all the way to the right, initiating a second cycle of operation identical to that previously described. Thus it is apparent that the piston 42 will start and complete one cycle of operations if the lever 98 is shifted clockwise and released before the cycle is completed, and that if the lever is not released, the piston 42 will continue to operate through repeated cycles until the lever

is released, after which the piston will come to rest the next time that it reaches its uppermost position. As will be apparent, the reversal of the platen 46 at the bottom of its stroke may be made to occur in response to pressure rather than position by removal of the dog 116 and opening the valve 130.

If during any part of the cycle an emergency should arise necessitating immediate stopping or reversal of the piston 42, the lever 136 can be operated counterclockwise to open connections through the pilot valve 132. If the lever 136 be thus shifted while the piston 42 is moving downwardly, it will be seen that communication is established from the conduit 36 (which is under pressure through conduit 146), ports 2 and T of valve 132, and conduit 144 to the connection 88. Since the spool 58 is in its right-hand position on the down stroke of piston 42, oil entering the cylinder 68 will shift the spool 58 toward the left discharging oil from the cylinder 78 through connection 90, conduit 148, ports 1 and P of valve 132 and conduit 142 to conduit 38. The conduit 38 is in communication with the tank while the spool 58 is in its right-hand position. As soon as the spool reaches its center position this communication is blocked so that oil can no longer discharge from the cylinder 78 through the connections described. The piston 42 is thus brought to rest substantially instantaneously by shifting lever 136.

It will be noted that during this emergency shifting of the spool 58, conduit 108 is connected to tank and conduit 110 is connected to pressure in line 38. Inasmuch as the communication of conduits 108 and 110 with the cylinders 68 and 78 is through the restrictors 80 and 82 it will be seen that only a limited quantity of oil entering the emergency connection 88 will be discharged to tank through the restrictor 80, the remainder being effective to shift the piston 64. Likewise at the left end of valve 26, the pressure oil entering from conduit 110 through restrictor 82 and discharged to tank through the connection 90 will be limited in quantity. Thus the press is brought to a stop on its working stroke by downward actuation of the lever 136.

If, on the other hand, the press should be on a returning stroke and an emergency arise, the lever 136 may be likewise shifted downwardly to establish the same connections through the valve 132. Under these conditions, the spool 58 being in its leftmost position and the line 38 being under pressure, oil from this line will flow through the conduit 142, ports P and 1 of valve 132 and emergency connection 90 to the cylinder 78. The spool 58 thus shifts to the right discharging oil from cylinder 68 through connection 88, conduit 144, ports T and 2 of valve 132 and conduit 148 to conduit 38 which is in communication with the tank at this time. Inasmuch as the lever 88 would normally have been released prior to shifting the lever 136, the detent 84 is in the path of the shoulder 82 so that the spool 58 can only shift to the right as far as its center position. During this rightward shifting the communication of cylinder 78 with the tank through conduit 110 is restricted by the restrictor 82, while the pressure connection of cylinder 68 through conduit 108 is likewise restricted by the restrictor 80, thus permitting the emergency connections to predominate in shifting the valve spool 58 as previously described.

Obviously the two levers 136 and 88 can be connected for operation from a single control element arranged in abutting relation to each lever so that the single element when shifted in one direction (clockwise) away from its neutral position will operate the lever 88 and when shifted in the opposite direction away from neutral will actuate the lever 136. The spring biases acting on levers 136 and 88 will normally hold such control element in neutral position.

Likewise it will be understood that foot valve 48 may be omitted if it is desired to utilize a different means for supplying pressure fluid to conduit 104 for operating the pilot circuits controlled by valve 100. For example, the beveling at land 62 may be made such as to produce sufficient back pressure in line 18 when spool 58 is centered to operate the pilot circuit, and the line 104 may then be connected to line 18 instead of line 38. On the other hand, an auxiliary source of pilot pressure independent of the main operating circuit may be utilized.

While the form of embodiment of the invention as herein disclosed constitutes a preferred form, it is to be understood that other forms might be adopted, all coming within the scope of the claims which follow.

What is claimed is as follows:

1. In a hydraulic power transmission system the combination with a source of pressure fluid and a double-acting reversible fluid motor of a directional control valve having forward, neutral and reverse positions for controlling the flow of fluid to the motor to respectively advance, stop and retract the motor, a pilot motor for shifting the control valve, pilot control means for causing the control valve to shift between the forward and reverse positions at the completion of each stroke, a detent arranged in the path of movement of the control valve from reverse to forward position to hold the valve in neutral position, means for retracting said detent to start operation of the motor through repeated cycles of advancing and retracting strokes while said detent is held retracted, and a second pilot control means connected with said pilot motor and shiftable in a single direction for causing shifting of said control valve in either direction depending on whether it lies in the forward or reverse position.

2. In a hydraulic power transmission system the combination with a source of pressure fluid and a double-acting reversible fluid motor of a directional control valve having forward, neutral and reverse positions for controlling the flow of fluid to the motor to respectively advance, stop, and retract the motor, a pilot motor for shifting the control valve, pilot control means for causing the control valve to shift between the forward and reverse positions at the completion of each stroke, a detent arranged in the path of movement of the control valve from reverse to forward position to hold the valve in neutral position, means for retracting said detent to start operation of the motor through repeated cycles of advancing and retracting strokes while said detent is held retracted, and emergency control means connected with said pilot motor and shiftable in a single direction in a manner to shift the control valve in a direction opposite to that dictated by the pilot control means when the emergency control means is actuated.

RAYMOND C. GRIFFITH.
